Primary Examiner — Paula Greene*(74) Attorney, Agent, or Firm* — Perkins Coie LLP**CLAIM**

The ornamental design for an interactive board, as shown and described.

DESCRIPTION

FIG. 1 is a perspective view of the interactive board showing my new design;

FIG. 2 is a front elevational view of the interactive board showing my new design;

FIG. 3 is a left side elevational view of the interactive board showing my new design;

FIG. 4 is a bottom plan view of the interactive board showing my new design;

FIG. 5 is a top plan view of the interactive board showing my new design;

FIG. 6 is a rear elevational view of the interactive board showing my new design; and,

FIG. 7 is a right side elevational view of the interactive board showing my new design.

The broken lines form no part of the claimed design.
